Nasal Metered Dose Inhaler Features No-Drip System [on-line] PharmPro.com newsletter, posted on May 12, 2010, [retrieved from the internet]. <<http://www.pharmpro.com/products/2010/05/packaging-Nasal-Metered-Dose-Inhaler>>.*

Primary Examiner — Ian Simmons
Assistant Examiner — Eleni H Aldridge

(57) **CLAIM**
The ornamental design for an inhaler, as shown and described.

DESCRIPTION

FIG. 1 is a top perspective view of the inhaler showing our new design in a first configuration;

FIG. 2 is a front elevational view of the inhaler in the first configuration;

FIG. 3 is a right side elevational view of the inhaler in the first configuration;

FIG. 4 is a rear elevational view of the inhaler in the first configuration;

FIG. 5 is a left side elevational view of the inhaler in the first configuration;

FIG. 6 is a top plan view of the inhaler in the first configuration;

FIG. 7 is a bottom view of the inhaler in the first configuration;

FIG. 8 is a top perspective view of the inhaler in a second configuration with the cover portion shown in a raised condition;

FIG. 9 is a front elevational view of the inhaler in the second configuration;

FIG. 10 is a right side elevational view of the inhaler in the second configuration;

FIG. 11 is a rear elevational view of the inhaler in the second configuration;

FIG. 12 is a left side elevational view of the inhaler in the second configuration;

FIG. 13 is a top plan view of the inhaler in the second configuration; and,

FIG. 14 is a bottom plan view of the inhaler in the second configuration.

The broken lines in the figures are for illustrative purposes only and form no part of the claimed design.
